THREAD CASE RETAINING DEVICE FOR
SEWING MACHINESAlfred S. Clark, Beverly, Mass., assignor to United
Shoe Machinery Corporation, Flemington, N. J.,
a corporation of New Jersey

Application April 11, 1944, Serial No. 530,497

2 Claims. (Cl. 112—196)

The present invention relates to bobbin or locking thread case retaining devices for lockstitch sewing machines of the type in which the thread case is mounted for easy removal from within a rotary loop taker or shuttle for carrying loops of needle thread about the thread case.

In this type of sewing machine, the thread case is removed from the machine for replenishment of the supply of locking thread and replaced after a new supply has been inserted. To hold the thread case in position and to prevent it from rotating with the loop taker, suitable thread case engaging means is provided in the form of a swinging retainer pivotally supported on the frame of the machine for movement toward and from the thread case. In the machine disclosed in United States Letters Patent No. 473,870, granted April 26, 1892, upon an application filed in the names of Zachary T. French and William C. Meyer, the parts are so arranged that it is possible to hold the thread case manually in position while swinging the retainer toward and from the thread case. When the retainer forms a part of a cover or door for a protecting case such as is disclosed in United States Letters Patent No. 1,302,597, granted May 6, 1919, upon an application of Thomas H. Seely, it is impossible to hold the thread case in position manually while swinging the cover toward and from the thread case. Machines of this type are intended to be operated with waxed thread, the wax from the thread frequently causing the thread case to adhere to the retainer so that, when the retainer is swung open, the thread case comes with it, falling to the floor and becoming damaged or resulting in inconvenience.

In United States Letters Patent No. 1,471,930, granted October 23, 1923, upon an application filed in the name of William G. Trohon, a length of resilient wire is bent with a number of coils and a curved substantially horizontal arm of the wire extends across the front of the thread case between the thread case and the retainer. With such a resilient arm, the thread case is held in place when the retainer is swung open and at the same time the thread case may be removed manually merely by flexing the wire to one side. The formation of coils in the wire to provide the necessary amount of yielding movement for easy flexure of the wire while removing the thread case, however, is detrimental to the strength of the wire and the arm of wire which extends across the front of the thread case is so located that a loop of thread being carried by the shuttle about the thread case may, under some circum-

stances, become impaled on the wire. As a result, the wire is flexed violently while the impaled loop of thread is being contracted toward the work. Such flexure may weaken the wire further or change its shape, particularly along those parts within the coils so that, under ordinary operating conditions, frequent replacement may be necessary.

The objects of the present invention are to 10 avoid the difficulties above enumerated and to provide simplified and improved means for preventing displacement of the locking thread case in a lockstitch shoe sewing machine of the type referred to even though the thread case retainer 15 is swung to open position or the machine is operated through a few sewing cycles without engagement of the retainer with the thread case. The principal features of the invention accordingly reside in a sewing machine of the type referred to provided with a hook needle, a locking thread case mounted for easy removal from the machine and a loop taker for carrying loops of needle thread about the locking thread case in which there are provided means for preventing 20 displacement of the thread case comprising a spring arm extending across the exposed side of the loop taker with one end bent across the side of the thread case in the direction of movement of the thread in the needle loop while the loop 25 is being carried by the loop taker about the thread case.

The loop taker of the machine in which this feature of the invention is embodied is constructed in a conventional manner with a needle loop entering beak at the root of which is formed a throat arranged to carry each loop of needle thread in a circular path about the locking thread case. In the illustrated form of the invention, the horizontal arm of the displacement preventer extends across the loop taker outside the circular path of the throat so that there is no possibility of a needle loop becoming impaled while being carried about the thread case.

These and other features of the invention will 45 be clearly understood from the following description, the appended claims, and the accompanying drawing in which

Fig. 1 is a view in front elevation of a portion 50 of a shoe sewing machine embodying the invention;

Fig. 2 is a plan view of the loop taker, thread case and thread case retainer together with means for preventing displacement of the thread 55 case illustrated in Fig. 1; and

Fig. 3 is a detail perspective view of the improved displacement preventer.

The machine illustrated in the drawing except as hereinafter described is the same as that disclosed in the patents above referred to and is provided with a loop taker in the form of a shuttle 10 which is rotatably oscillated in a shuttle race 12 at the front of the machine. The shuttle race constitutes a part of a casing 14 secured by a bolt 16 to a lug 18 on the machine frame. The locking thread is contained in a thread case 20 which is easily removable from a cylindrical recess in the front of the shuttle, it being retained in the recess and prevented from oscillation with the shuttle by means of a swinging retainer 22 in the form of a heat retaining case or hood, more fully illustrated and described in the Seely patent.

The means for preventing displacement of the locking thread case while swinging the retainer 22 toward and from the thread case in the present invention is formed from a short piece of high-tensile strength steel wire which is bent to provide a mounting eye 24 surrounding the head of the bolt 16 by means of which it is secured to the machine frame and a forwardly inclined substantially horizontal arm 26 bent slightly rearwardly to enable the arm to enter between the retainer 22 and the thread case 20. No coils are formed in the arm between its point of attachment with the machine frame and the extreme end of the arm in a manner to reduce the strength of the wire or to form irregularities upon which thread or foreign material may become entangled. At the extreme free end 27, the horizontal arm of the displacement preventer is bent through a gradual curvature of relatively large radius in order to extend downwardly across a side of the thread case in the direction of movement of a loop of needle thread being carried about the thread case by the looper. A portion of the thread in the needle loop is indicated at 28.

It is evident that, as the shuttle which is formed with a beak 30 picks up each loop of thread, the thread will slide toward a throat 32 formed at the root of the beak and be carried within the throat about the thread case through a circular path, indicated by the dot-dash line 34. The horizontal arm 26 of the wire is located a substantial distance above and outside the path 34 taken by the throat of the shuttle, and the only possible engagement of the thread in the needle loop with the wire is at its extreme down-

wardly extending end 27. Since this end is bent in the direction in which the needle loop moves during normal sewing operations, there is no chance for the loop to become impaled on the end of the wire.

In removing the thread case from the machine, the retainer 22 is opened, and there is sufficient flexibility in the horizontal arm 26 of the displacement preventer to enable removal of the thread case either by brushing the preventer wire aside or withdrawing the thread case forwardly until it clears the shuttle and then moving the thread case laterally. The absence of small radius coils in the preventer not only avoids the possibility of weakening the wire which, during its manufacture is subject to a high degree of tensile strength and brittleness by drawing, but also eliminates several steps in the manufacture of the preventer. Thus, the expense of manufacture is reduced and a device of greater durability results.

The nature and scope of the invention having been indicated and a machine embodying the several features in their preferred form having specifically been described, what is claimed is:

1. A sewing machine having stitch forming devices, including a locking thread case mounted for easy removal from the machine, and a loop taker for carrying loops of needle thread about the locking thread case, and means for preventing displacement of the thread case comprising a spring arm extending across the loop taker with one end bent across a side of the thread case in the direction of the movement of a loop of needle thread while being carried by the loop taker about the thread case.

2. A sewing machine having stitch forming devices, including a locking thread case mounted for easy removal from the machine, and a loop taker provided with a needle loop entering beak at the root of which is formed a thread engaging throat arranged to carry each loop of needle thread in a circular path about the locking thread case, and means for preventing displacement of the thread case, comprising a spring arm extending outside the circular path of the loop taker throat with its thread case engaging end inside said circular path bent across a side of the thread case in the direction of movement of the thread in the needle loop, while being carried by the loop taker about the thread case.
